4 Claims. (Cl. 80—1)

This invention relates to rolling mills for the production of metal plates, sheets and the like and to means for cleaning the roll surfaces thereof. More particularly, this invention relates to means for controlling the force exerted by the cleaning means on the roll surfaces.

Heretofore, it has been the usual practice to provide such cleaning means with some mechanism for manually controlling the forces exerted by such means on the work roll surfaces such as spring and screw means. Such practice possesses certain inherent disadvantages particularly with regard to the exertion of unequal forces throughout the axial length of the cleaning means. The prior art mechanisms, being of a manually adjustable type, did not provide adequate adjusting characteristics. The operators, while adjusting the forces at each end of the cleaning means were unable to exactly ascertain the amount of adjustment necessary on each extremity. Manifestly, in the event the operators tightened down on the mechanism at one end of the cleaning means slightly more than the mechanism at the opposite end of the cleaning means a greater force would be applied to the working rolls at one end than at the other, thereby ultimately resulting in a correspondingly greater wear of one portion of the working surface of the cleaning means than at other portions. It will be obvious that such uneven wear would necessitate more frequent replacements of the cleaning means and a correspondingly greater amount of lost time for the entire rolling mill of which the instant invention is an integral part.

Accordingly, it is the general object of the instant invention to avoid and overcome the foregoing and other difficulties of and objections to known cleaning means adjusting mechanisms by the provision of an improved mechanism for hydraulically controlling the forces applied by the cleaning means to the working roll surfaces whereby such forces are equal throughout the entire axial length of the working rolls.

Another important object of the invention is to produce an automatic hydraulically controlled cleaning roll in combination with the working roll of a rolling mill.

A further object of the invention is to produce a hydraulically controlled mechanism for controlling the force exerted by the cleaning means of a rolling mill which may be readily and economically manufactured.

Still another object of the invention is to produce hydraulically actuated means to selectively control the engagement pressure at either end of a cleaning means of a rolling mill in contact with an associated working roll in such a manner that the force exerted by said cleaning means on said working roll is equal throughout the entire engaging or contacting surface.

A still further object of the invention is to produce a hydraulic system for selectively controlling the force exerted by a cleaning means of a rolling mill for rolling metal which may be applied to existing rolling mills with a minimum amount of effort and cost.

These and other objects of the invention which will become apparent from a reading of the description of the

invention as set forth in detail hereinafter are achieved by the provision in a rolling mill, the combination of a base frame, a pair of cooperating positively driven working rolls journaled in said frame, a cleaning means in association with each of said working rolls, a pair of hydraulically operated extensible members for each of said cleaning means and a hydraulic system for effecting movement of said hydraulic cylinder with respect to said piston-like member, whereby the contact pressure between said cleaning rolls and said working rolls at either end of said cleaning means may be selectively controlled.

Figure 1 is a side elevational view with a portion thereof shown in section of one stand of a rolling mill incorporating the instant invention wherein a rotating brush type cleaning means is employed.

Figure 2 is a front elevational view, partly in section, of the mill stand of Figure 1.

Figure 3 is an enlarged sectional view taken along line 3—3 of Figure 2 with portions thereof shown in section.

Figure 4 is a sectional view of the invention taken along line 4—4 of Figure 3.

Figure 5 is a sectional view of the cleaning roll drive assembly taken along line 5—5 of Figure 4.

Figure 6 is a side elevational view with a portion thereof shown in section of one stand of a rolling mill incorporating the instant invention wherein a stationary type cleaning means is employed.

Figure 7 is a schematic illustration of the hydraulic actuating circuit.

With particular reference to Figures 1 and 2, there is shown the general arrangement of one stand of a rolling mill having a base frame 10 supporting a pair of cooperating working rolls 12. The working rolls 12 are journaled in suitable bearings (not shown) disposed within the upright sections 14 of the frame 10. Suitable drive motors (not shown) are provided to impart rotary motion to the working rolls 12. The power from these motors may be directly transmitted through a single drive shaft from each motor or through any other suitable power transmission means.

The upright sections 14 of the frame 10 are also adapted to carry a pair of back-up rolls 18 which are journaled in suitable bearings (not shown) disposed within the frame 10. In practice, one back-up roll 18 is provided to cooperate with each of the working rolls 12 in such a manner that the peripheral surface of each back-up roll 18 is in positive contact with its associated working roll 12 and serves to reduce the deflection of the working roll from the loads encountered in rolling metal.

A substantially horizontal table 22 is suitably affixed to the upright sections 14 of the frame 10 and is provided with a stripper 23 at one end in close proximity to the lower working rolls 12, and a plurality of rollers 24. It will be readily apparent that the rollers 24 provide a support for the metal stock which is caused to pass between and be flattened by the cooperating pair of working rolls 12. A second stripper 25 is provided in close proximity to the upper working roll 12. Strippers 23 and 25 are provided to remove the rolled metal from the working rolls 12 to which it tends to adhere.

Suitable cleaning means or devices are provided, one for each of the working rolls 12. Such cleaning means may be either a rotating type as shown in Figures 1 through 5 or a stationary type as shown in Figure 6. With reference to Figures 1, 2 and 3 said cleaning means comprises a pair of cleaning rolls 26 adapted to be in contact with the outer peripheral surface of the working rolls 12. Said cleaning rolls 26 have a suitable cleaning material 28 covering the outer periphery thereof. The cleaning material 28 may be comprised of groups of radially extending bristles of suitable material such as metal, plastics, fiber, etc., which act to remove any

foreign material which may become adhered to the work contacting surface of the working rolls 12. The cleaning rolls 26 are adapted to be driven from suitable motors 16 through a suitable flexible power transmitting apparatus. In an embodiment of this invention shown in Figures 1 through 5 such apparatus includes an angle drive assembly 30; an extensible telescoping shaft 32; and a cleaning roll drive assembly 36. For purposes of simplicity, the operation will be described in connection with and specific reference will be made only to the lower cleaning roll 26 and its drive assembly. It is understood that the upper cleaning roll 26 and its associated drive is substantially identical with the lower one.

Drive motor 16 is suitably mounted on the roll stand base frame 10 and is coupled to the angle drive assembly 30. The angle drive assembly 30 may be of any of the conventional types such as for example the gearing arrangement shown in Figure 25, page 12 of "Five Hundred and Seven Mechanical Movements" by Henry T. Brown, 21st ed., 1908, pub. by Brown & Seward, 216 Broadway, New York, N.Y. The output shaft of the angle drive assembly 30 is coupled to the cleaning roll drive assembly 36 through a universal joint 34, telescoping shaft 32, and a second universal joint 35. The telescoping drive shaft 32 is comprised of an inner and an outer member so arranged as to transmit positive rotary motion while being capable of extension or contraction.

As shown in Figure 5, the cleaning roll drive assembly 36 comprises a shaft 38, one end of which is coupled to the second universal joint 35 and mounted on bearings 40. The other end of the shaft 38 is provided with a bevel gear 42. The bevel gear 42 is adapted to mesh with and in turn drive a second bevel gear 44 which is mounted on and suitably keyed to an intermediate shaft 46 which is rotatably supported by bearings 48. A spur gear 50 is also mounted on and suitably keyed to the shaft 46. The spur gear 50 is adapted to mesh with and drive an associated spur gear 52 which is integrally mounted on the axle 54 of the cleaning roll 26. It will be noted upon examination of Figure 5 that the axle 54 of the cleaning roll 26 is journaled or rotatably supported by bearings 56 and 57. The entire cleaning roll drive assembly 36 may be suitably covered by a housing 58, as clearly shown in connection with the Figures 3 and 4. Referring to Figures 3 and 4, it will be seen that the entire cleaning roll drive assembly 36, including the cleaning roll axle 54, is supported by a sliding member 60 which in turn is supported between a pair of guide rails 62 and 64. The guide rails 62 and 64 are disposed beneath the horizontal table 22 and suitably secured to the base frame 10. It is to be understood that the member 60 is adapted to slide along a longitudinal axis between the guide rails 62 and 64.

The member 60 is provided with a cylindrical recess 66 adapted to receive a piston 68. Near one of the terminal portions of the piston 68, there is formed an annular recessed groove 70 adapted to receive a hydraulic packing 72. The hydraulic packing 72 fits snugly against the inner surface of the recess 66 and provides a fluid tight seal between the piston 68 and the recess 66. The extreme terminal portion of the piston 68 is provided with a projection 74 of reduced diameter to provide an annular space for hydraulic fluid even when the piston 68 has fully penetrated into the cylindrical recess 66. The terminal portion of piston 68 opposite the projection 74 has a cylindrically concave surface 76 provided to mate with a mating convex cylindrical end portion 78 of a restraining member 80. The opposite extremity or terminal portion of the restraining member 80 has an aperture 82 formed therein. A removable pin 84 is provided to fit through apertures formed in the guide rails 62 and 64 and through the aperture 82. Thus, the restraining member 80 is prevented from moving in a direction away from the piston 68 and likewise, the piston

68 is prevented from moving in a direction toward the aperture 82.

The sliding member 60 is provided with a fluid receiving fitting 86 which is adapted to form a portion of the conduit for the fluid to be passed to the cylindrical recess 66. Thus, when oil or other hydraulic fluid is forced into the opening between the inner wall of the cylindrical recess 66 and the projection 74 of the piston 68, the latter being rigidly fixed against longitudinal movement, the pressure exerted by the incoming fluid will cause the sliding member 60 and its associated axle 54 of the cleaning roll 26 to move toward its associated working roll 12 of the mill stand.

With particular reference to Figure 3, it will be seen that the opposite terminal portion of the cleaning roll axle 54 from that described hereinabove is supported by suitable bearings 88 which in turn are carried by a sliding member 90 similar to the sliding member 60 of the cleaning roll drive assembly 36. The slide member 90 is provided for sliding engagement between a pair of guide rails 92 and 94, similar to the guide rails 62 and 64 mentioned hereinabove. The sliding member 90 is provided with a cylindrical recess 96 in the end portion thereof. A piston 98, similar to piston 68, is received within the recess 96 and a restraining member 100 similar to the restraining member 80 is employed in conjunction therewith. The sliding member 90 is provided with a fluid receiving conduit provided for the passage of fluid into the cylindrical recess 96. It is to be understood that the sliding assemblies for supporting and effecting the sliding movement of both terminal portions of the cleaning roll axle 54 are essentially the same.

The operation of the piston 98, the sliding member 90, and the restraining member 100 is substantially the same as the operation of the corresponding elements acting on the opposite end of the cleaning roll axle 54, such that when fluid is forced into the cylindrical recess 96 through the fluid receiving fitting 102, the respective end of the cleaning roll 26 is moved toward the working roll 12.

Manifestly, in light of the above description, it is readily discernible that movement of either or both ends of the cleaning roll axle 54 can be effected by forcing a hydraulic fluid into the respective cylindrical recesses 66 and 96, through the fittings 86 and 102, respectively. For purposes of clarification it is to be understood that a description of the upper assemblies for effecting movement of the cleaning rolls toward their associated working rolls is not deemed necessary inasmuch as the apparatus and operation thereof is substantially identical with that described above.

While rotating type cleaning means have been shown and described above it is to be distinctly understood that stationary type cleaning means may be employed. With reference to Figure 6 said stationary cleaning means comprises a pair of stationary cleaning members 27 adapted to be in contact with the outer peripheral surface of the working rolls 12. Said cleaning members 27 may comprise a channel type member 29 of a suitable material preferably metal, and having a contact member such as a wooden board or plank 19 contained therein. Such wooden board or plank 19 may be applied directly to the surface of the working rolls 12 or a suitable buffering of cleaning material may be applied to said wooden board or plank 19. In lieu of a wooden board or plank a suitable stationary brush means could be employed for contacting the surface of working rolls 12. Such brushes may be fabricated of any suitable material such as metal, plastic, fiber, etc., which act to remove any foreign material which may become adhered to the work contacting surface of the working rolls 12. One end of cleaning member 27 may be supported by a sliding member 60 which in turn is supported between a pair of guide rails 62 and 64. The guide rails 62 and 64 are disposed beneath the horizontal table 22 and suitably secured to the base frame 10. It is to be understood that the mem-

ber 60' is adapted to slide along a longitudinal axis between the guide rails 62 and 64.

The sliding member 60' is constructed substantially the same as sliding member 60, having a cylindrical recess adapted to receive a piston. Since the structure of the cylindrical recess and piston is substantially the same as cylindrical recess 66 and piston 68 of the embodiment shown in Figures 1 through 5, they will not be described in detail. As with the previously described embodiment one terminal portion of said piston has a cylindrically concave surface provided to mate with a mating convex cylindrical end portion of a restraining member 80, identical to the restraining member 80 shown in Figures 1 through 5. Restraining member 80 is mounted within guide rails 62 and 64 in the same manner as previously described in connection with the embodiment of this invention shown in Figures 1 through 5. The opposite end of stationary cleaning member 27 is supported by a sliding member similar to sliding member 90 of the previously described embodiment which sliding member is supported and operated in the manner as described above. The operation of the sliding member 60' and the sliding member similar to member 90 is substantially the same as the operation of the corresponding elements described above in connection with the embodiment shown in Figures 1 through 5, such that when fluid is forced into the cylindrical recesses through the fluid receiving fittings the respective end of the stationary cleaning member is moved toward the working roll 12.

As can be seen from the drawings, guide rails 62, 64, 92 and 94 are mounted on their respective upright sections 14 independently from horizontal table 22 and stripper 23. Similarly, the upper guide rails 62' and 64' are mounted on upright sections 14 independently from stripper 25. In practice guide rails or guiding members 62, 64, 92 and 94 may be mounted on horizontal table 22, while upper guide rails or guiding members 62' and 64' may be mounted on stripper 25, however, independent mountings are preferable.

Operation of the cleaning means of this invention, e.g. cleaning rolls 22, or stationary cleaning members 27 results in wearing down the cleaning material whereby periodic replacement becomes necessary. With particular reference to Figures 3 and 4 the method for removing cleaning rolls 26 involves first removing pins 84 and 103. Restraining members 80 and 100 may then be removed permitting sliding members 60 and 90 to be moved along guide rails 62, 64, 92 and 94 away from working rolls 12. By continuing the movement of sliding members 60 and 90 past the end of guide rails 62, 64, 92 and 94 furthest removed from working rolls 12, e.g. the left end as shown in Figure 1, sliding members 60 and 90 and the associated cleaning roll 26 may be removed from the rolling mill. The worn cleaning roll 26 may then be easily removed from sliding members 60 and 90 and replaced by a new cleaning roll 26. By reversing the above procedure sliding members 60 and 90 may be engaged in guide rails 62, 64, 92 and 94, restraining members 80 and 100 replaced and pins 84 and 103 replaced.

While replacement of cleaning rolls 26 of the embodiment of this invention shown in Figures 1 through 5 has been specifically described above it is to be understood that stationary cleaning members 27 of the embodiment shown in Figure 6 may be replaced in the same manner.

Attention is now directed to Figure 7 which illustrates a suitable hydraulic system for effecting the desired control and adjustment of the cleaning rolls 26 relative to their associated working rolls 12. The hydraulic circuit is described only in connection with one of the rolling mill stands, the circuits for the other stands being substantially identical thereto. A pump 104 driven by a motor 105 is provided to pump a hydraulic fluid contained within a fluid reservoir 106 through a fluid conductor

10 pipe 108 to a header 110. The pipe 108 may be provided with a relief valve 112. A plurality of fluid conduits or pipes 114, corresponding in number to the number of mill stands to be controlled, are connected to the header 110 and each lead to a T joint 116 which is adapted to divide the fluid flow at each mill stand assembly, one half of the fluid being permitted to pass to the upper portion of the mill stand and the remaining amount of fluid being permitted to pass to the lower portion. For purposes of simplification only the lower portion of the mill stand assembly will be discussed to correspond to the foregoing description of the apparatus. Those parts of the hydraulic system serving the upper portion of the mill stand assembly which are identical to corresponding parts serving the lower portion of the mill stand assembly have identical numerals with the prime (') designation added thereto.

20 A fluid conduit or pipe 118 is connected to the lower part of the T joint 116 and is adapted to extend to another T joint 120 which is provided to divide the fluid flowing through the pipe 118 into fluid conduits or pipes 122 and 124. The pipe 122 is connected to the fluid receiving fitting 86 through a suitable pressure reducing valve 126 and T joint 127 and the pipe 124 is connected to the fluid receiving fitting 102 through a suitable pressure reducing valve 128 and the T joint 129. From each T joint 127 and 129 a fluid conduit 131 and 133, passes therefrom through suitable fixed orifices 130 and 132 to constantly bleed a portion of the hydraulic fluid back to the hydraulic fluid reservoir 106. Also, a valve 134 may be provided in the pipe 118 to completely restrict the flow or passage of fluid therethrough.

30 It may be readily ascertained from the above description that pressure may be selectively applied to either or both ends of the cleaning roll axle 54 by adjusting the respective pressure reducing valves 126 and 128. This result is effected due to the fact that increasing the pressure of the hydraulic fluid passing to a given fluid receiving fitting tends to increase the pressure within the respective cylindrical recess thereby forcing the respective sliding member and its respective end of the cleaning roll axle 54 toward the working roll 12 of the mill.

40 According to the provisions of the patent statutes, I have explained the principles and mode of operation of my invention, and have illustrated and described what I now consider to represent its best embodiment. However, I desire to have it understood that, within the scope of the appended claims, the invention may be practiced otherwise than as specifically illustrated and described.

50 What is claimed is:

1. In a rolling mill comprising a base frame, a pair of cooperating working rolls journaled in said frame, and a cleaning device operatively associated with each of said working rolls, said cleaning device comprising a cleaning roll, journal means on each end of said cleaning roll, a pair of sliding members one mounting each of said journal means and slidably supported by a pair of guiding members affixed to said frame, each of said sliding members having a cylindrical recess which receives a piston-like member having a portion which extends out of said cylindrical recess to engage a restraining member pivotally affixed to said frame, a motor imparting rotary motion to said cleaning roll and fluid pressure means including means for equalizing the pressure to each said sliding member for effecting movement of said sliding member with respect to its associated piston-like member whereby the contact pressure between said cleaning rolls and said working rolls at either end of said cleaning rolls may be selectively controlled and the pressure exerted by said cleaning rolls on said working rolls equalized along the entire lengths of said cleaning rolls.
2. In a rolling mill as set forth in claim 1 wherein said fluid pressure means comprises pumping means, a

hydraulic fluid reservoir connected to the suction of said pumping means, a fluid conduit connecting the delivery of said pumping means to a header, a plurality of fluid conduits each of which passes from said header through a pressure reducing valve followed by a T joint to each of said cylindrical recesses, each T joint having a fluid conduit passing therefrom through a fixed orifice to said hydraulic fluid reservoir.

3. A rolling mill cleaning device of the type described comprising in combination with a pair of cooperating working rolls journalled in a frame, a roll cleaning device cooperatively associated with each of said working rolls, said cleaning device comprising a cleaning roll, journal means on each end of said cleaning roll, said cleaning roll being movable into and out of peripheral engagement with a working roll, means for supporting said cleaning roll adjacent said working roll secured to said journal means and slidably supported with respect to said frame whereby said journal means and cleaning roll will also be slidably supported with respect to said frame, said 20 slidably supported means including a sliding member provided with a cylindrical recess, a piston-like member inserted in said recess and having a portion which extends out of said recess, a pivotally mounted restraining member engageable with said last mentioned portion projecting from said recess, said restraining member also being pivotally affixed to said frame, means including a telescopic drive means for rotating said cleaning roll and a fluid pressure means including means for equalizing the 25 pressure to each said sliding member for effecting movement of said sliding member with respect to said piston-like member whereby the contact pressure between the cleaning roll and the working roll at either end of said cleaning roll may be selectively controlled and the contact pressure along the entire length of said cleaning roll 30 equalized with respect to said working roll.

4. In a rolling mill comprising a base frame, a pair of cooperating working rolls journalled in said frame and a cleaning device operatively associated with each

of said working rolls, said cleaning device comprising a cleaning means, a pair of mounting means one on each end of said cleaning means, a pair of sliding members one mounting each of said mounting means and slidably supported by a pair of guiding members affixed to said frame, each of said sliding members having a cylindrical recess which receives a piston-like member having a portion which extends out of said cylindrical recess to engage a restraining member pivotally affixed to said frame, and 5 fluid pressure means including means for equalizing the pressure to each said sliding member for effecting movement of said sliding member with respect to its associated piston-like member whereby the contact pressure between said cleaning means and a working roll at either end of said cleaning means may be selectively controlled and the pressure exerted by said cleaning means on said working roll equalized along the entire length of said cleaning means.
